UNITED STATES PATENT OFFICE.

HERBERT C. JARVIS, OF TORONTO, ONTARIO, CANADA.

MANUFACTURE OF WALL PAPER.

Application filed January 30, 1922. Serial No. 532,737.

To all whom it may concern:

Be it known that I, HERBERT C. JARVIS, of the city of Toronto, in the county of York, Province of Ontario, Canada, a subject of the King of Great Britain, have invented 5 certain new and useful Improvements in the Manufacture of Wall Paper, of which the following is a specification.

This invention relates to improvements in 10 the manufacture of wall paper as described in my prior United States Patent 1387724 of August 16th, 1921.

When wall paper is printed as therein described by means of a printing roller longer 15 than the width of the paper being printed, the overlapping ends of the roller will deposit color on the blanket or surface on which the paper is supported, so that, if no remedy be provided, the color would soon 20 accumulate in such fashion as to interfere with the clean printing of the paper, and my object therefore is to devise means for over- coming this trouble.

I attain my object in the manner herein- 25 after described and illustrated in the accom- panying drawings in which—

Fig. 1 shows a part of a strip of wall paper and a printing roller in the act of 30 printing the pattern on the paper, a wider strip of paper being shown underlying the strip of wall paper;

Fig. 2 a plan view of a modified form of 35 a strip of wall paper produced in accordance with my invention, an underlying strip of paper being shown in connection therewith; and

Fig. 3 a side elevation showing diagram- 40 matically one method of employing the underlying strip of paper shown in Figs. 1 and 2.

In the drawings like numerals of refer- 45 ence indicate corresponding parts in the dif- ferent figures.

I aim to make it possible to print wall 50 papers either without selvages or with only one selavage, and this I effect in the follow- ing manner. Instead of making the printing surface of the printing rollers of the exact width of one or more repeats of the 55 pattern, I extend the pattern about one- quarter inch at each end of the roller, these extensions being partial repeats of the pattern to be printed by the roller, see Fig. 1.

In printing wall papers without any sel- 55 vage, I use a paper of the exact width of one or more transverse repeats of the pat-

tern and therefore about one-half inch nar- 60 rower than the printing surface of the roller. Now, as a strip of paper can be guided through the printing machine to within one- quarter inch of exact alinement with the printing rollers for lengths up to many yards, and as the paper is the exact width of one or more horizontal repeats of the pat- 65 tern, the pattern is printed so that one side of the paper will match the other exactly, one margin being exactly complementary to the other in adjacent strips up to the lengths ordinarily cut.

In printing the wall paper with one sel- 70 vage only, I use paper about one-half inch wider than the horizontal repeat of the pat- tern (see Fig. 2) and guide the paper through the printing machine so that the edge of the printing surface of the roller 75 will overlap one edge of the paper about one-quarter inch more or less, thus leaving a selvage along the other edge.

When hanging paper with one selvage, 80 the edge without selvage may be laid over the selvage of the last hung strip and ex- tended over the printed portion to the line where the pattern exactly matches, thus a perfect matching of the design may be obtained, the selvage being entirely covered. 85

When wall paper is printed in the manner described, it is evident that the overlapping printing rollers will deposit color on the blanket or surface on which the paper is supported, and that if no remedy be pro- 90 vided the color would soon accumulate in such fashion as to interfere with the clean printing of the paper. While the trouble might be overcome by providing wiping de- 95 vices to remove the color from the blanket, I prefer to run a web of paper under the wall paper being printed which is sufficiently wider than the wall paper to receive the imprint of the overlapping roller ends. This 100 underlying paper may be dried and used many times over, or if of sufficiently cheap stock may be rolled up with the wall paper, in which case it would serve to protect the ends of the roll from damage, and when the paper is being cut into strips for hanging, 105 each strip will have a blank strip under- lying it projecting sufficiently at each side to keep the paste used in hanging from spreading on to the table or under the edges of the wall paper or onto the edges of un- 110 derlying strips.

In Fig. 1, I show an underlying strip of

paper 1 projecting at each side beyond the sides of the strip of wall paper. This is the arrangement which will be employed when paper is printed without a selvage, at either 5 side. In Fig. 2, the underlying strip 1 is shown projecting at one side only, namely, that side which is without selvage. In Fig. 10 3, the underlying strip of paper 1 is shown as an endless band passing around rollers 2, which in practice will be spaced sufficiently far apart so that the paper has time to dry before it returns to the printing position.

What I claim as my invention is:—

- 15 1. A process of printing a strip of wall paper which consists in superimposing the strip of wall paper on another strip of paper and printing said strip of wall paper with a printing roller having its printing surface wider than the exposed strip of wall paper when hung, the underlying strip of paper 20 being adapted to receive the imprint of a projecting end of the roller.
- 25 2. A process of printing a strip of wall paper which consists in superimposing the strip of wall paper on underlying paper and printing said strip of wall paper with a printing roller having its printing surface wider than the exposed strip of wall paper when hung and projecting beyond the wall paper at each 30 side, the underlying paper being adapted to receive the imprint of the projecting ends of the rollers.
- 35 3. A process of printing a strip of wall paper which consists in superimposing the

strip of wall paper on another strip of paper and printing said strip of wall paper with a printing roller having its printing surface wider than the exposed strip of wall paper when hung, the underlying strip of paper 40 being adapted to receive the imprint of a projecting end of the roller, drying the wall paper and the underlying paper, and rolling them up together.

4. A process of printing a strip of wall 45 paper with a repeat pattern, which consists in superimposing the strip of wall paper on another strip of paper and employing a printing roller formed with a repeat pattern and having its printing surface wider 50 than the exposed width of the strip of paper when hung and printing said strip with the printing surface overlapping one edge of the strip, the paper being of a width not less than a suitable repeat of the pattern. 55

5. A process of printing a strip of wall paper with a repeat pattern, which consists in superimposing the strip of wall paper on another strip of paper and employing a 60 printing roller formed with a repeat pattern and having its printing surface wider than the exposed width of the strip of paper when hung and printing said strip with the printing surface overlapping both edges of the 65 strip, the paper being of a width exactly equal to a suitable repeat of the pattern.

Signed at Toronto, Canada, this 19th day of January, 1922.

HERBERT C. JARVIS.
